DRAWING FRAME FOR SPINNING MACHINES

Kurt Siegfried Hohloch, Ebersbach (Fils), Germany, assignor of one-half to Süddeutsche Spindelwerke Zinser, Ebersbach (Fils), Württemberg, Germany, a joint-stock company of Germany, and one-half to Vereinigte Kugellagerfabriken Aktiengesellschaft, Stuttgart-Bad Cannstatt, Württemberg, Germany, a joint-stock company of Germany

Application April 24, 1950, Serial No. 157,731

Claims priority, application Germany
May 28, 1949

7 Claims. (Cl. 19—135)

1

This invention relates to textile machinery and more especially to the drawing frames forming part of spinning and other textile machines.

It is more especially concerned with the type of drawing frame carrying pivotless drawing rollers and with an improvement of the weighting device for the top rollers of the drawing set.

Drawing frames are known, in which the weighting of the top rollers is effected by means of a spring acting on a plurality of top rollers, the weighting action of the spring being transmitted onto the individual rollers by means of a saddle. Combinations of this kind have been used in drawing frames provided with pivots for the top rollers and also for pivotless rollers, but they involve the drawback that whenever the drawing set is being adjusted, the ratio of mutual weighting of the individual rollers undergoes a change which has an unfavorable influence on the spinning operation. Therefore, as a rule, a second saddle must be resorted to, if adjustment within wide limits is required.

In the drawing frames according to the present invention each top roller of the drawing set has its own weighting spring which is so arranged that the degree of loading exerted by it on its roller does not undergo a change when the drawing set is adjusted. Obviously this enables a distribution of the load over the individual rollers to be dispensed with.

The arrangement according to this invention becomes particularly simple if the holders of the individual pivotless top rollers are resiliently yielding members. In this case the associated yielding holders of a drawing set can be guided and supported in a rail, preferably of U section, extending above the top rollers in parallel to the drawing set, their weighting effect on the individual rollers always remaining the same regardless of the adjustment of the set.

This arrangement is further improved by fixing on the rail together with the yielding top roller holder also a holder for the clearer roller in such a manner that this latter holder can be shifted together with the yielding top roller holder. In this combination the clearer roller always automatically assumes the correct position relative to the top roller. I prefer to so fashion the holder for the clearer roller that it embraces the channel-shaped rail, guiding the loading spring at its bottom part and keeping it under preliminary tension when the drawing frame is relieved of the load.

The guide rail for the resilient top roller holders is preferably supported at its upper end for

2

rocking motion relative to the holder bar and its front end is positively connected with the reversing rail. Since in this case the reversing rail is relied upon to support part of the top roller weight, I prefer reinforcing it and bolting it to the roller stand.

Owing to this arrangement of the weighting device any detached hooks or combed slivers can be dispensed with altogether and the calendar 10 rollers, on which laps might form, can be mounted in place and removed without requiring the load on the drawing frame to be relieved.

The member connecting the reversing rail with the channel rail will secure this latter 15 against any sidewise displacement whereby an accurate parallel guiding of the top and bottom rollers is obtained.

In the drawings affixed to this specification and forming part thereof an embodiment of this 20 invention is illustrated diagrammatically by way of example.

In the drawings

Fig. 1 is a diagram showing, partly in vertical section, a drawing frame according to this invention, the parts being in operating position.

Fig. 2 is a similar view of the frame, however, with the top rollers in raised position.

Fig. 3 is a partial plan view, drawn to a smaller scale, and,

Figs. 4 to 6 are sectional detail views.

Referring to the drawings and first to Figs. 1—3, 1 is the U-shaped guide rail or channel and 2, 3 and 4 are the resilient holders, guided in this channel, of the top rollers 5, 6 and 7, respectively, their top ends being fixed to the rails by means of screw bolts 8, 9 and 10, respectively, which also connect to the rail the holders 11, 12 and 13 for the clearer rollers (Fig. 4). Near the free ends of the resilient holders 2, 3 and 4 are fixed by means of rivets gripping springs 14, 15 and 16, respectively, or similar means for supporting the top rollers 5, 6 and 7 in a resilient or yielding manner. The rail 1 is supported by its top end for rocking movement on the holder bar 17. Near its free end it can be positively connected by means of the hook-shaped members 19 and 20 (Figs. 2 and 5A) with the reversing rail 18 fixed to the roller stands.

Fig. 3 shows a longitudinal slot 24 formed in 50 the middle web of the rail 1 which serves for adjusting the set, a graduation 25 (Fig. 3) being provided near this slot.

Fig. 4A shows on a larger scale the middle top roller 6 with its resilient holder 3 and the gripping spring 15. The screw bolt 9 fixes the holder

3 together with the holder 12 of the clearer roller 21 to the rail 1, the holder 12 keeping the holder 3 under preliminary tension. This figure also shows that the clearer roller 21 is always maintained in the same position relative to the top roller 6 it is associated with.

Fig. 4B shows the clearer roller holder 12 as embracing the rail 1 and guiding the resilient holder 3 at its free end.

Figs. 5A and 5B illustrate the connection between the reversing rail 18 and the channel rail 1, a member 19 embracing the reversing rail and being formed as a hook at its top end. This hook-shaped portion is formed with an open notch 30 in which rests the channel rail 1. On the rail 1 there is mounted for rocking movement at 31 another hook-shaped part 20 which together with the part 19 enables a readily disengageable connection to be established between the top roller holder 1 on the one hand and the reversing rail 18 and the roller stand 18 on the other hand. If this connection is so organized, for instance by means of a spring (not shown) acting on the part 20, as to be established automatically as soon as the members 19 and 20 contact each other, all that is needed for weighting the drawing frame is to move the rail 1 downwardly until the hook 20 has gripped the hook 19. In order to disengage again the parts, a slight pressure exerted on the top end 32 of the double armed lever 20 and on the bottom of rail 1 will be sufficient to release the latter.

Fig. 6 illustrates the way in which two ends of the reversing rail 18 are connected to the roller stand 23 by means of screw bolts 22.

I wish it to be understood that I do not desire to be limited to the details shown and described for obvious modifications will occur to a person skilled in the art.

I claim:

1. A pivotless drawing frame for textile machines comprising in combination, a set of top rollers, a separate loading spring holder for each top roller, a channel-shaped rail extending above said rollers and forming a guide for said holders and a clearer roller holder adjustably fixed to said rail and associated with and maintaining each loading spring holder under preliminary tension.

2. A pivotless drawing frame for textile machines comprising in combination, a set of top rollers, a separate loading spring holder for each top roller, a channel-shaped rail extending above said rollers and forming a guide for said holders, a reversing rail and a readily disengageable connecting device positively coupling said two rails.

3. A pivotless drawing frame for textile machines comprising in combination, a set of top rollers, a separate loading spring holder for each top roller, a channel-shaped rail extending above said rollers and forming a guide for said holders, a reversing rail and a pair of hook-shaped connecting members, one on each rail, resiliently coupling said two rails.

4. A pivotless drawing frame for textile machines comprising in combination, a set of top rollers, a separate loading spring holder for each top roller, a channel-shaped rail extending above said rollers and forming a guide for said holders, a reversing rail and a pair of hook-shaped connecting members, one on each rail, resiliently coupling said two rails, a notch in the hook-shaped connecting member of said reversing rail forming a seat for said channel-shaped rail.

5. Apparatus for guiding and pressing top rolls

of textile drawing machines, comprising, in combination, an elongated support extending over the drawing plane and having an underside directed toward the drawing plane; a plurality of spring means distributed along the length of said support and having upper end portions respectively fixed to the underside of said support, said plurality of spring means extending downwardly from said support toward the drawing plane and being carried only by said support at said underside thereof, said spring means respectively having lower free end portions distant from said support; a plurality of sets of top rolls each of which includes a shaft connected to the rolls, said sets of top rolls being respectively located adjacent to said plurality of spring means and beneath said support; and a plurality of attaching means respectively engaging said shafts of said sets of top rolls on opposite sides thereof to turnably maintain said shafts in a predetermined position, said plurality of attaching means respectively attaching said shafts only to said lower free ends of said plurality of spring means and respectively forming units with the latter to transfer to said sets of top rolls, respectively, forces exerted by said spring means in a direction downwardly from said support, said spring means and attaching means being entirely free except for engagement of said spring means with said support and said attaching means with said shafts of said sets of top rolls.

6. Apparatus for guiding and pressing top rolls of textile drawing machines, comprising, in combination, an elongated support extending over the drawing plane and having an underside directed toward the drawing plane; a plurality of spring means distributed along the length of said support and having upper end portions respectively fixed to the underside of said support, said plurality of spring means extending downwardly from said support toward the drawing plane and being carried only by said support at said underside thereof, said spring means respectively having lower free end portions distant from said support; a plurality of sets of top rolls each of which includes a shaft connected to the rolls, said sets of top rolls being respectively located adjacent to said plurality of spring means and beneath said support; a plurality of attaching means respectively engaging said shafts of said sets of top rolls on opposite sides thereof to turnably maintain said shafts in a predetermined position, said plurality of attaching means respectively attaching said shafts only to said lower free ends of said plurality of spring means and respectively forming units with the latter to transfer to said sets of top rolls, respectively, forces exerted by said spring means in a direction downwardly from said support, said spring means and attaching means being entirely free except for engagement of said spring means with said support and said attaching means with said shafts of said sets of top rolls; releasable holding means connected to said support for releasably holding the same in an operative position on the apparatus and for preventing upward movement of said support during operation of the apparatus; and means for adjusting the location of said upper end portions of said spring means along the length of said support.

7. Apparatus for guiding and pressing top rolls of textile drawing machines, comprising, in combination, an elongated support extending over the drawing plane and having an underside directed toward the drawing plane; a plurality of sub-

stantially V-shaped leaf springs distributed along the length of said support and each having opposite free end portions one of which is connected to the underside of said support, said leaf springs extending downwardly from said support toward the drawing plane and being carried only by said support at said underside thereof, the other of said free end portions of each leaf spring being located distant from said support; a plurality of sets of top rolls each of which includes a shaft connected to the rolls, said sets of top rolls being respectively located adjacent said other end portions of said leaf springs, respectively; a plurality of attaching means respectively engaging said shafts of said sets of top rolls on opposite sides thereof to turnably maintain said shafts in a predetermined position, said plurality of attaching means respectively attaching said shafts only to said other free end portions of said leaf springs and respectively forming units with the latter to transfer to said sets of top rolls, respectively, forces exerted by said leaf springs in a direction downwardly from said support, said

leaf springs and attaching means being entirely free except for the engagement of said springs with said support and said attaching means with said shafts of said sets of top rolls; and releasable holding means connected to said support for releasably holding the same in an operative position on the apparatus and for preventing upward movement of said support during operation of the apparatus.
